UNITED STATES PATENT OFFICE.

JOHN LINCOLN GISH, OF SOUTH BEND, INDIANA.

SANITARY WATER-CLOSET BOWL.

1,128,243.

Specification of Letters Patent.

Patented Feb. 9, 1915.

Application filed January 26, 1914. Serial No. 814,415.

To all whom it may concern:

Be it known that I, JOHN LINCOLN GISH, a citizen of the United States, residing at South Bend, in the county of St. Joseph and State of Indiana, have invented a new and useful Sanitary Water-Closet Bowl, of which the following is a specification.

The object of my present invention is to construct a sanitary water closet bowl, in such a manner; firstly, that the said bowl will have a sanitary usefulness; secondly, that the said bowl will be noiseless in its operative procedure; and thirdly, that the said bowl will be provided with means, whereby a removable union is formed, between the said bowl and the lead bend or trap beneath the floor line, and still the said union be properly closed and sealed, in accordance to all sanitary demands, upon such connecting parts.

Figure, 1., is the sanitary water closet bowl, with a portion of the bowl A., and a portion of its standard B., removed, in order to fully expose its various parts. Fig. 2., is 25 a vertical section thereof, taken through the intake tube I., down through the trap E''.

Similar letters, refer to similar parts, throughout the figures.

A., is the bowl.

30 B., is the standard, supporting the bowl A., over its base C.

C., is the base, receiving the standard B.

H., is a lead bend or trap beneath the floor line.

35 n'', n''', indicates the water level, which stands in the trap H.

i., i'', is a removable connecting pipe.

e., is a groove formed on the pipe i., i''.

40 F., is a collar, securely fastened, to the closed channel-way E., E', E''.

n., n', indicates the water level, which stands in a trap, formed in the closed channel-way E., E', E''.

E., E', E'', is the closed channel-way, 45 leading from the opening D.

b., is a section of a seat, for the said bowl A. a., is a section of a cover for the said seat b., said a., and b., are connected to the bowl A., in the usual manner.

50 s., s', is a flushing rim, to the bowl A.

D., is an opening in the side of the bowl A.—the said opening D., forms the entrance to the closed channel-way E., E', E''.

I., is the intake tube, for the flushing 55 stream leading to the bowl A.

I', is the inlet opening to the intake tube I.

h., h', are small jet openings, within the flushing rim s., s', leading from the intake tube I.

o., o', o'', are small jet openings, leading 60 from the intake tube I., and located at a point, beneath the water level m.

m., indicates the water level, which stands in the bottom of the bowl A., and in the bottom, of that portion, of the channel-way 65 E., E', E'', which is between the opening D., and a point corresponding, to the point, marked E.

The special features of this device are described as follows:—first, the flushing 70 stream is allowed to enter the bowl A., through the openings o, o', o'', second, the force of the flushing stream is applied at the periphery or outer edge of the contents of the bowl A., and beneath the water level 75 m.; third, the force of the flushing stream is directed against the inner curved wall of the bowl A., in such a manner, as to obtain the guiding direction, of the said inner curved wall, upon the flushing stream, and 80 produce a whirling motion of the water within the bowl A., thereby producing effects, by means of centrifugal force and action, to discharge the contents of bowl A., as soon as the intake of water, raises the 85 water level, above the water level m.

The fourth feature of importance is the opening D., in the side of the bowl A., and forming the entrance into the channel-way E., E', E'',—the said opening D., is large 90 and roomy, having its lowest line on a level with the bottom of the bowl A., and its top line, above the flushing level, thus affording an easy entrance, for the contents of the bowl A.

The fifth feature, is the closed channel-way E., E', E'', which leads from the opening D., and follows an upward spiral course, around the outside of the bowl A., to a point, corresponding to the point 100 marked E., where the said channel-way then descends to near the bottom of the part B., where again the said channel-way bends upon itself and forms a trap, for holding water, as indicated by n., n'.—from this 105 trap, onward, the said channel-way, takes a downward course and ends at a point within the connecting pipe i., i''. The upward spiral portion of the said channel-way, between the opening D., and the point 110 marked E., is of special importance, for the reason, that the elevation of the point

marked E., above the bottom of the bowl A., determines the height of the water level $m.$; and also it is to be noticed, that the passage-way, through this same portion of the said channel-way, is of the same size, as the opening D., thereby placing the top line of this portion of the said channel-way, above the flushing level, and thereby affording an easy passage-way, for the contents of the bowl A.

With the parts thus mentioned and described, the device operates as follows,—the bowl A., with its standard B., and base C., having been joined to the trap H., by means of the connecting pipe $i.$, $i'.$, and the intake pipe I., having been joined, at the inlet I', with any suitable means supplying a flushing stream,—the flushing stream is allowed to enter the intake pipe I., immediately a small quantity of the flushing stream enters the flushing-rim $s.$, $s'.$, by way of the jet nozzles $h.$, $h'.$, and the sides of the bowl A., are moistened to prevent soil clinging thereto, as the contents of the bowl A., is moved onward. Simultaneously with the moistening of the sides of the bowl A., the flushing stream enters the bowl A., through the openings $o.$, $o'.$, and applying the force of the flushing stream, at the periphery or outer edge of the contents of the bowl A., and beneath the surface of the water level $m.$ Also, the force of the flushing stream is directed against the inner curved wall of the bowl A., in such a manner, as to produce a whirling motion of the water within the bowl A., and thereby produce effects, by means of centrifugal force and action, whereby the contents of the bowl A., is swept into and through the opening D., where the centrifugal action is further increased by the flushing stream, which enters through the opening $o''.$ The contents of the bowl A., having been swept and pulled into and through the opening D., by means of centrifugal force and action, the same whirling motion is still carried onward, until the contents of the bowl A., has passed the point, marked E. The point E., having been passed, the contents of the bowl A., is carried forward, by the action of gravity, and the siphonic action at $n.$, $n'.$, and $n''.$, $n'''.$, after which the discharge is conducted to a drain pipe to a place of disposal. After the flushing has been completed,—water refills the traps at $n''.$, $n'''.$, and $n.$, $n'.$, and replaces the water in the bowl A., to the water level $m.$, and leaves the device ready to repeat its work.

In view of the fact that the openings $o.$, $o'.$, $o''.$, are located beneath the water level $m.$,—the force of the flushing stream and its action upon the contents of the bowl A., is a noiseless procedure, and inasmuch as the siphonic action at $n.$, $n'.$, and $n''.$, $n'''.$, takes place with in the closed channel-way E, E', E'', and at

some distance removed, from the opening D, no noise is heard from that source of action, thereby making the device above described, a noiseless sanitary water closet bowl.

Therefore, what I do claim as my invention and desire to secure by Letters Patent is,—

1. In a water closet bowl operated by fluid passing through the bowl, the combination of a bowl provided with a flushing rim, inlet and outlet openings, the inlet opening discharging tangentially, a standard adapted to support said bowl, a base adapted to receive said standard, a closed channel-way in the said standard adapted to connect the outlet opening from the said bowl to a connecting pipe, said channel-way provided with an inlet opening having its top line above the inlet level and adapted to coöperate with the centrifugal effects produced by the inlet to flush said bowl, said channel-way further provided with a water seal, $n.$, $n'.$, adapted to prevent return of gases from the drain pipe.

2. In a water closet bowl operated by fluid passing through the bowl,—a bowl having an outlet provided with means for determining the water level and an intake pipe provided with discharge openings, beneath the water level $m.$, adapted to apply the force of the flushing stream along the periphery or outer lines of the contents of the said bowl, thereby producing effects by centrifugal action, to discharge the contents of said bowl at a predetermined time.

3. In a water closet bowl operated by fluid passing through the bowl,—a bowl having a flushing pipe provided with discharge openings beneath the water level $m.$, adapted to apply the force of the flushing stream along the periphery of the contents of the said bowl, an outlet opening in the side of said bowl provided with means for establishing a water level, said opening having its lowest line on a level with the bottom of said bowl and its top line above the flushing level, thereby coöoperating with the flushing stream, to allow the contents of the said bowl to be swept, into and through the said opening, by means of effects produced by centrifugal action, to discharge the contents of said bowl, at a predetermined time.

4. A water closet bowl provided with a tangentially discharging inlet, an outlet opening through its wall and a channel-way adapted to connect the outlet opening to a drain pipe, said outlet opening having its top above the water level and coöoperating with the flushing stream to discharge the contents of said bowl by means of centrifugal action, said channel-way further provided with an elevation corresponding to the point E., whereby the water level $m.$, is determined.

5. A water closet bowl provided with a

tangentially discharging inlet and an outlet opening in the side of the bowl, said opening having its top above the inlet level and coöperating with the flushing stream to discharge the contents of said bowl by means of centrifugal action.

5 In testimony whereof I have signed my

name to this specification in the presence of two subscribing witnesses.

JOHN LINCOLN GISH.
